HAND FIRE EXTINGUISHER

Filed July 5, 1927

UNITED STATES PATENT OFFICE

HENRY C. HAYS, OF DETROIT, MICHIGAN, ASSIGNOR TO CONTINENTAL CAN COMPANY, INC., OF NEW YORK, N. Y., A CORPORATION OF NEW YORK

HAND FIRE EXTINGUISHER

Application filed July 5, 1927. Serial No. 203,481.

The invention relates to new and useful improvements in hand fire extinguishers, and more particularly to the type of fire extinguisher wherein the fire extinguishing compound is thrown from the container for extinguishing a fire.

An object of the invention is to provide a supporting means whereby a container of the above type may be suspended in any readily accessible place by means which is detachably connected to the closure for the container, and so disposed relative thereto as to positively remove the closure when the container is pulled upon.

A further object of the invention is to provide a suspending means for the fire extinguisher of the above type, which is in ring form with an integral tab adapted to be used for supporting the closed container, and wherein said ring is placed between a portion of the closure and the container so that when said container is pulled upon, the ring will pry the closure from the container body.

In the drawings which show by way of illustration one embodiment of the invention—

Figure 1 is a perspective view of the upper portion of a fire extinguisher embodying the improvements;

Fig. 2 is a sectional view on the line 2—2 of Fig. 1, on an enlarged scale, and

Fig. 3 is a perspective view of the ring for removing the closure from the container and for supporting the fire extinguisher.

The invention is directed to a hand fire extinguisher comprising a container body and a closure which is preferably frictionally held on the container body so as to seal the container body, but so as to be readily detachable therefrom. The container body is provided with an apertured top portion formed with a friction seating wall all the way around the opening in the top. The container body is closed by a closure having a centrally depressed portion adapted to engage said friction seat on the top for sealing the container and holding the closure firmly on the container body.

The closure has a projecting flange overlying the top. Located beneath the flange and surrounding the depressed portion of the closure is a metal ring which is provided with an integral tab extending vertically above the outer edge of the closure. This tab is located substantially in the plane of the outer wall of the container body, and is used for supporting the container. The container body is supplied with the fire extinguishing compound, and by pulling on the container body, the closure is removed therefrom so that the container body is opened and the contents of the container body may be thrown upon the fire for extinguishing the same.

Referring more in detail to the drawings, the fire extinguisher includes a container body 1, preferably of metal, which is tubular in form. The fire extinguishing compound, preferably in powdered form, is placed in the container body. The upper end of the container body is provided with an apertured top 2 which is secured to the body portion of the container by a double seam 3. This apertured top is formed with a depending vertical flange 4 forming a friction seat. The container body is closed by a cover or closure 5 which is provided with a centrally depressed portion 6 adapted to engage the vertical friction wall 4 for firmly securing the closure to the container body and for sealing the same. The closure is provided with a flange 7 which overlies the top of the container body. This flange extends to a point substantially in line with the inner wall of the container and is folded underneath as indicated at 8.

The invention is directed particularly to the means for supporting a container of the above type. This means consists of a metal ring 9 having a central opening 10 therethrough. The edge of the ring adjacent the opening 10 is slightly turned upwardly as indicated at 11 in Fig. 2 of the drawings. The top of the container is slightly depressed within the double seam, so as to form a housing or recess for this ring. The ring is provided with an integral tab 12 which is perforated at 13, and this tab is

secured to the ring at the outer edge thereof. The tab is carried by an offset neck portion 14, so that said tab when placed vertically, will lie directly over the double seam and extend upwardly outside of the extreme edge of the closure.

When the parts are assembled as shown in Fig. 1, with the container body supplied with the fire extinguishing compound, the fire extinguisher then is suspended from a suitable device adapted to extend through the perforation 13 in the tab 12. In case of fire, the body portion of the container is seized and pulled upon. This will cause the ring to pry the closure from the container body. It is well known that when removing the friction closure from the container, it is a great advantage to start the movement of the closure on its friction seat at substantially one point in the circumference of the friction seat. In effect, this is what is accomplished in the present structure. When the container body is pulled, the ring will be held rigidly from movement directly beneath the suspending means for the tab, and this will cause the portion of the friction seat in the region of the support to move on the closure. In other words, the force which separates the closure from the container is at the extreme outer edge of the closure and substantially at one side of the closure. The force, however, will continue all the way around the closure, and the ring will positively separate the closure from the container. It is noted that this ring is entirely independent of the closure and container, and is confined to the assembled container and closure by the placing of the closure in the container. After the parts are assembled with the ring between the closure flange and the container body, it serves as a positive means for separating the closure from the container body.

Having thus described the invention, what I claim as new and desire to secure by Letters-Patent, is—

A hand fire extinguisher comprising a container body having a top with an opening therethrough surrounded by a substantially vertical friction wall, a closure having a central depressed portion adapted to engage said friction wall, and a flange overlying the top of the container and terminating within the limits of the outer wall of the container, a flat metal ring surrounding said central depressed portion of the closure and located beneath the flange thereof, said ring having a projecting neck portion extending beyond the edge of the flange and a vertically extending supporting tab formed integral therewith and disposed substantially in alignment with the wall of the body of the container, said tab having a perforation therethrough whereby said container may

be suspended by said tab and the cover withdrawn from the container by a pull exerted on the body portion of the container.

In testimony whereof, I affix my signature.
